(57) **CLAIM**

The ornamental design for augmented reality glasses, as shown and described.

DESCRIPTION

FIG. 1 is a front, top, and right-side perspective view of augmented reality glasses;

FIG. 2 is a front elevational view of the augmented reality glasses shown in FIG. 1;

FIG. 3 is a rear elevational view of the augmented reality glasses shown in FIG. 1;

FIG. 4 is a right elevational view of the augmented reality glasses shown in FIG. 1;

FIG. 5 is a left elevational view of the augmented reality glasses shown in FIG. 1;

FIG. 6 is a top plan view of the augmented reality glasses shown in FIG. 1; and,

FIG. 7 is a bottom plan view of the augmented reality glasses shown in FIG. 1.

The surface shading, if any, illustrated in the drawings is provided merely to highlight the contour of the design; it is not intended to be illustrative of texture or gloss.

1 Claim, 5 Drawing Sheets
